UNITED STATES PATENT OFFICE

149,589

DESIGN FOR A CABINET FOR SOUND
REPRODUCING APPARATUS

David C. Rockola, Chicago, Ill., assignor, by mesne assignments, to Rock-Ola Manufacturing Corporation, Chicago, Ill., a corporation of Delaware

Application February 15, 1947, Serial No. 136,937

Term of patent 14 years

(Cl. D56—4)

To all whom it may concern:

Be it known that I, David C. Rockola, a citizen of the United States and a resident of Chicago, in the county of Cook and State of Illinois, have invented a new, original, and ornamental Design for a Cabinet for Sound Reproducing Apparatus, of which the following is a specification, reference being had to the accompanying drawings, forming a part thereof.

Fig. 2 is a side elevational view of the cabinet, the rear wall of the cabinet being plain and the opposite side wall not shown being similar to the side wall shown in the drawing.

I claim:

The ornamental design for a cabinet for sound reproducing apparatus, substantially as shown and described.

DAVID C. ROCKOLA.
